US00D606655S

(12) **United States Design Patent**
Wilkinson et al.

(10) **Patent No.:** US D606,655 S
(45) **Date of Patent:** ** Dec. 22, 2009

(54) **PORTABLE OXYGEN CONCENTRATOR**

(75) Inventors: **William R. Wilkinson**, Lakeway, TX
(US); **Allan Sten Westersten**, El
Dorado, CA (US); **H. David Shockley**,
Jr., Austin, TX (US)

5,060,506 A 10/1991 Douglas
5,060,514 A 10/1991 Aylsworth
5,099,837 A 3/1992 Russel et al.
5,108,467 A 4/1992 Schroter et al.
5,129,924 A 7/1992 Schultz

(73) Assignee: **Inova Labs, LLC**, Austin, TX (US)

(Continued)

(**) Term: **14 Years**

(21) Appl. No.: **29/320,511**

(22) Filed: **Jun. 27, 2008**

(51) **LOC (9) Cl.** **24-01**

(52) **U.S. Cl.** **D24/164**

(57) **CLAIM**

The ornamental design for a portable oxygen concentrator, as shown and described.

DESCRIPTION

FIG. 1 is a front-right-top perspective view thereof;

FIG. 2 is a back view thereof;

FIG. 3 is a front view thereof;

FIG. 4 is a left view thereof;

FIG. 5 is a right view thereof;

FIG. 6 is a top view thereof; and,

FIG. 7 is a bottom view thereof.

The broken lines in FIGS. 1 to 7 are included for the purpose of illustrating portions of the portable oxygen concentrator that form no part of the claimed design.

1 Claim, 4 Drawing Sheets
